W. H. McNUTT.

SELF CLOSING CAN.

APPLICATION FILED SEPT. 6, 1913.

1,122,623.

Patented Dec. 29, 1914.

UNITED STATES PATENT OFFICE.

WILLIAM H. McNUTT, OF NEW YORK, N. Y., ASSIGNOR TO CARRIE EMMA OWEN, OF FRANKLIN, NEW YORK.

SELF-CLOSING CAN.

1,122,623.

Specification of Letters Patent. Patented Dec. 29, 1914.

Application filed September 6, 1913. Serial No. 788,419.

To all whom it may concern:

Be it known that I, WILLIAM H. McNUTT, a citizen of the United States, and resident of New York city, in the county of New 5 York and State of New York, have invented certain new and useful Improvements in Self-Closing Cans, of which the following is a specification.

This invention relates to automatic closures or lids for cans or vessels designed for holding readily inflammable or explosive fluids, such as gasolene and the like; and is especially designed for use with cans provided with a long filler tube of sheet metal 15 having small flame-proof apertures and which projects down into the can, for the purpose of preventing back fire of ignited vapor or flame, into the can, that would cause an explosion.

20 The object of the present invention is to provide a lid that is hinged to the outer end of the projecting tube, with a form of elongated spring that serves to automatically close the lid whenever it has been opened 25 and released and retain it in the closed position; and which spring is readily detachable from the inner face of the lid, and also at its lower end from the lower portion of the filler tube, whereby upon such spring becoming defective it can be easily removed by disconnecting it from the lid and from the lower portion of the tube, and without removal of the tube from the can, and also without the employment of any tools.

30 A further object of the invention is to provide in connection with the described spring arrangement, a closure or stopper for the lower or inner end of the filler tube that will be entirely non-corrosive, and 35 which can be merely inserted in the tube and retained without special securing means in its proper position.

In the accompanying drawing illustrating one embodiment of my invention, Figure 1 45 shows in section the upper portion of a can with my invention applied; and Fig. 2 is a plan view of the lid.

As shown in the drawing the top 3 of the can 2 has a central opening 4, at which is 50 secured a bushing 5 whose bore registers with the opening 4, the bushing having a flange 6 at the bottom by which it is secured to the top 3 by suitable means such as rivets. A tube 7 of comparatively thin sheet 55 metal and of an outside diameter to fit into

the bore of the bushing 5, is secured in the lower portion of the bushing by suitable means such as bolts 8; and which tube 7 is provided throughout its length with minute flame-proof openings. A suitable closure is 60 provided for the lower end of the filler tube 7, that is of sufficient strength to carry a loop at its center to receive a spring whose tension serves to close a lid at the top of the bushing. I preferably provide a tapered 65 plug 9 formed out of wood, that is forced into the lower end of the filler tube 7, and frictionally held therein, as well as by the tension of the spring as will be set forth. By forming this plug of wood, there is no 70 possible danger of the closure being loosened or damaged from corrosion, as sometimes occurs where a metal closure is employed for such purpose.

At the central portion of the inner face of 75 the plug 9 I secure a loop for the purpose, as stated, of engaging a spring, and as shown I provide a bolt 10 passing through an axial bore in the plug, and having a loop 11 at the top. The bolt is shown as provided with 80 nuts 12 on its lower threaded end; and I further provide washers 13 and 14 on the two faces of the plug 9 to receive the strain of the bolt, and also to protect the wooden plug. At the upper end of the bushing 5 I 85 provide a lid 15 that is suitably hinged to the bushing, such as by a lug 16 being pivoted to ears 17 on the bushing, whereby the lid can swing from the closed position shown, to an open position as indicated in 90 broken lines; the opening of the lid being facilitated by a bail 18 swinging on ears 19 at the outer face of the lid 15. On the inner face of the lid 15 at the center, I secure a loop 20, that may be in the form of a closed 95 eye similar to the eye 11 of the bolt 10 at the bottom of the tube; and this eye is preferably secured to the lid so that its plane is parallel to the axis on which the lid swings, as shown. A coil spring 21 is provided of a length to have its extremities detachably engaged with the loop 20 on the lid, and with the loop 11 at the lower end of the filler tube. Each of these detachable connections, at the ends of the spring, is 100 preferably in the form of a hook and loop; that is, the upper end of the spring is connected with the lid by a hook on one of these members engaging a loop on the other member; and the lower end of the spring is con- 110

nected with the plug 11, by a hook on one of these members and a loop on the other member.

In the construction shown I secure a hook 22 at the upper end of the spring 21, that can be easily caused to engage the loop 20 in the bottom of the lid, and released therefrom by merely swinging it a short distance out of its normal position. And I secure a 10 similar hook 23 to the lower end of the spring, that can be readily caused to engage the loop 11 projecting up from the plug 9. This long spring member 21 will serve to normally retain the lid in the closed position as shown. When access to the can is desired, the lid is engaged by its bail 18, and is swung back on its hinge, which action will put the spring under still further tension, obviously drawing the spring to one side of 15 the filler tube as indicated in broken lines, and as the coil spring is flexible the lid can be swung back to the position indicated by the broken lines, but the spring will at once return the lid to closed position upon release 20 of the lid.

It will be readily understood that when it is desired to remove the spring for any cause, the lid is opened and the spring grasped by the hand, and turned so that the 25 hook 22 can be drawn out of the loop 20, that will free the spring from the lid. Then by slight manipulation of the spring the lower hook 23 can be moved out of the loop 11 on the plug, when the spring is free 30 to be removed from the tube. Obviously, another spring can be attached in the same manner, by simply inserting it in the tube and causing its hook to engage the loop 11 on the plug, and then hooking the upper end 35 of the spring to the eye on the lid, the said plug remaining in place during both the detaching and attaching operations by reason of its frictional engagement in the tube end. By arranging the loop 20 parallel 40 with the axis of the lid, the hook 22 will take a position at right angles thereto as shown, and as the lid swings open the hook will swing on the eye, but will not become disengaged therefrom. Since the spring that 45 holds the lid is always under tension, the plug 9 will be drawn into the tube and securely held in this closing position. Being 50 formed of wood, the plug cannot become

loosened through chemical action, as sometimes occurs with a metal closure. The use 55 of the large washer 13 on top of the wooden plug, protects the plug, especially in the insertion and removal of the spring, as the hook cannot be jammed against the wooden surface.

Having thus described my invention, what I claim is:

1. The combination with a bushing adapted to be secured in a can opening, and a lid hinged to said bushing and provided with a depending loop, of a tube extending down from the bore of the bushing and provided with minute flame-proof openings; a tapered plug of yielding, non-corrodible material frictionally engaged in the lower end of said tube and provided with an axially located bolt having an upper terminal loop; and a coil spring disposed within said tube and provided at its opposite ends with hooks detachably engaged with the loops on said lid and said bolt, whereby upon disengaging the lid loop from the upper hook on said spring, the lower hook on said spring can be disengaged from the bolt-loop, said plug and tube remaining in place during such disengagement.

2. The combination, with a bushing adapted to be secured in a can opening, and a lid hinged to said bushing and provided with a depending loop; of a tube extending down from the bore of the bushing and provided with minute flame-proof openings; a tapered wooden plug frictionally engaged in the lower end of said tube and provided with an axial bolt having an upper terminal loop; washers arranged against the opposite faces of said plug to protect the same and to receive the strain of the bolt, and a coil spring disposed within said tube and provided at its opposite ends with hooks detachably engaged with the loops on said lid, and said bolt, whereby upon disengaging the lid loop from the upper hook on said spring, the lower hook on said spring can be disengaged from the bolt loop, said plug and tube remaining in place during such disengagement.

WILLIAM H. McNUTT.
